UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

DRAFT RIGGING.

Application filed December 15, 1921. Serial No. 522,576.

The invention relates to draft rigging for railway cars and more particularly to a rear draft casting and combined center filler brace.

5 The principal object of the invention is to provide in a single structure a body bolster center casting and rear draft lugs.

Another object of the invention is to provide in this construction means for suitably 10 supporting the truck center plate.

A still further object of the invention is to provide a casting of the character described wherein the metal is arranged so as to give the maximum strength value for the 15 minimum expenditure of material and to arrange the various elements of the casing so as to cause them to react to best advantage to the variety of forces to which they may be subjected from the several different 20 functions imposed upon a single integral casting.

A still further object of the invention is to provide a casting in such a form as to render the necessary parts of it accessible to inspection and to so construct the casting as to admit of the ready driving of the necessary attaching rivets.

A still further object of the invention is to so arrange the various structural elements of the casting as to make the same easy to mold and to avoid excess foundry loss by the elimination from the casting of shrinkage, cracks, checks, and other common causes of loss which are experienced in 35 casting large metal objects when due consideration is not given to the combination of thin and thick metallic sections.

Various other objects and features of the invention are hereinafter brought out 40 in a more detailed description of the particular modification of my invention which has been chosen for the purpose of illustration.

In the drawings:

45 Figure 1 is a view partially in plan and partially in longitudinal section, of a combined stop center brace and center bearing embodying my invention, the section being

taken on line 1—1 of Figure 2. In dotted lines I have illustrated the position of the 50 yoke of the draft rigging when in normal position.

Figure 2 is a longitudinal vertical section on line 2—2 of Figure 1, the direction of view being indicated by arrows at the 55 ends of the section line.

Figure 3 is a rear end view partially in elevation and partially in section, the section being taken on line 3—3 of Figure 2.

Figure 4 is a view in front elevation partially in plan and partially in section, the section being taken on line 4—4 of Figure 2, adjacent portions of the car being shown in dotted lines.

Throughout the specification and drawings like parts are designated by like reference characters.

In the preferred embodiment of the invention here illustrated, the casting 1 is provided with side walls 2 which are adapted 70 to contact and preferably conform to the inner faces of the draft or center sills 3 which are illustrated in dotted lines in Figure 4. The center sills 3 are preferably connected by a top cover plate 4 to form the usual box 75 center sill construction. The sills 3 are also preferably provided with inturned bottom flanges 5 so that in effect the lower portions of the sills are in the form of an I-beam and the upper portion of the sills in the form of 80 the ordinary rolled channel. The casting 1 is arranged to bridge between the sills 3 and to deliver all of the buffing forces thereto.

The casting 1 is provided with a bottom floor 6 which is approximately in line with the bottom edge of the side walls 2 except at the intermediate portion designated as 7, where the floor is diverted from its normal plane to conform to the upper surface of the inturned flanges 5 of the center sills. The 90 side walls 2 are connected in line with the body bolster 8, illustrated in dotted lines in Figure 4, by means of a transversely arranged upright wall or web 9, and formed on the upper portion of the wall or web 9 95 is a transversely extending flange 10. This

construction forms a beam across the center sill member so that when the car body rocks and the load is concentrated at one edge of the center plate 10, also illustrated in dotted lines in Figure 4, the casting will have sufficient beam strength to resist the forces to which it is under these conditions subjected. The thimble 11 which is adapted to receive the king bolt (not shown) is provided at the top with a closed wall 12 and is formed preferably in the transversely extending upright wall 9. The body bolster 8 is secured to the center sills in line with the downwardly extending intermediate portion 7 of the casting 1. The bottom tie member 13 of the bolster, which preferably extends directly under the portion 7 of the casting 1, is clearly indicated in dotted lines in Figure 4.

10 The portions of the side walls 2 of the casting 1 which are above the downwardly extending portion 7, are provided with rivet receiving openings 14 through which the securing rivets 15 are adapted to extend. Preferably I provide four vertical lines of rivet openings for the rivets 15 and these rivets, in addition to connecting the casting 1 to the center sills, also form means for connecting the portions of the bolster to the center sills and to the center casting. Additional rivet receiving openings 17 are provided forward of the rivet openings 15, as will be hereinafter more fully described.

20 The side walls 2 of the casting are extended forwardly of the upright rib and are provided with transversely arranged walls or inwardly extending flanges 18 which preferably form stop faces or lugs to engage the movable element of the draft rigging. In this manner the ordinary draft lugs are formed as an integral part of the body bolster center casting 1. The stop faces or flanges 18 are supported by a plurality of longitudinally extending ribs 19, 20, 21 and 22 which extend from the rear faces of the flanges 18 and from the inner faces of the adjacent side walls. It will be observed that the upper rib 19 preferably follows the line of the upper edge of the casting and that the casting, as defined by this rib, is higher at the forward or draft lug end than at the rear or bolster center filler end of the casting. This construction is devised in order to make the outer rivets 23 more accessible from the rear as it is sometimes necessary, in driving these rivets, to reach over the transversely extending flange 10.

30 The ribs 19 and 22, it will be observed from Figure 4, are formed by inwardly extending portions of the side walls 2, while the ribs 20 and 21 are formed by what may be termed a convolution or inwardly extending bend in each of the side walls 2. By so constructing the casting I provide in effect, a series of convolutions, the convo-

lutions formed between the ribs 19 and 20 and between the ribs 21 and 22 opening from the inner face of the casting, while the convolution between the ribs 20 and 21 opens from the outer face of the casting. By this construction I provide reinforcing flanges without increasing the thickness of the metal and provide the side walls with webs of substantially constant and uniform thickness.

40 The inner portions of the stop lugs 18 are spaced apart sufficiently to accommodate the rear end of the ordinary vertically arranged draft gear yoke 24, shown in dotted lines in Figure 1. The draft gear engaging face 25 of this yoke is preferably positioned in alignment with the outer faces of the lugs 18, while the rear end of the yoke is normally, preferably, spaced from a cross wall or transversely extending web 26 of the casting, which wall or web defines the length of the yoke receiving pocket. By this construction it will be evident that any yielding forward due to elongation of the yoke or to bending of the draft rigging parts, would cause the rear end of the yoke to come in contact with the transversely extending wall 26 which would act to prevent further rearward movement.

50 The transversely extending wall or web 26 is arranged in line with and may be considered as an extension of the portions 27 of the side walls 2. By this construction the entire rear end of the yoke, it will be observed, is surrounded by a continuous wall of metal. This not only forms a substantial buffering arrangement for the yoke when the necessity arises, but also provides liberal wearing surplus for the side edges of the yoke. In order to further strengthen the inner edges of the lugs 18, I preferably provide inwardly extending vertically arranged flanges 28 which connect the ribs 19 and 20 and 21 and 22, respectively. At their inner ends the flanges 19 and 22 merge, respectively, into the transversely extending flange 10^a and into the bottom wall or floor of the casting, while the intermediate ribs 20 and 21 merge into the upright rib 9 of the casting, as will be hereinafter described.

60 It will be noted that the bottom rib 22 is approximately on a line with the diverted portion 7 of the floor 6 of the casting. This rib is located somewhat above the lower plane of the floor 6 in order that it may clear the inturned flange 5 of the channel draft sills. In other words, this rib is in effect a continuation of the angularly disposed portion 7 of the floor 6 and its angular form gives it great rigidity to resist the forces to which it may be subjected.

70 Spaced from the floor portion 6 of the casting 1 and extending transversely of the casting, is a second wall or floor web 29 which extends from the cross web 9 forwardly to

the cross web 26, preferably in line with the ribs 21. The ribs 21 are in reality continuations of this transverse web 29. The rib 29 is of course adapted to receive forces from the rib 21 and from the transversely extending flange 26. This rib has also an important function in that it forms a gusset to hold the side walls 2 of the casting in alignment in cases where more load is delivered to one of

10 the center sills than to the other, that is it provides means for preventing relative movement between the channel draft or center sills.

15 Adjacent the upper edge of the flange or web 26 I provide a rearwardly extending flange 30 which is adapted to further reinforce the said flange 26.

A vertical web 31 preferably extends longitudinally of the casting and approximately on the center line thereof and serves 20 to support the floor 6 and to brace this floor and tie the same to the upright transversely extending web 9. I preferably extend this web both above and below the transversely extending horizontally disposed web 29 and 25 also extend the same forwardly so as to intersect the wall or web 26 and the flange 30 thereof. It will be thus apparent that this vertically extending web thus forms a sturdy resisting medium to any forces which may at 30 times be delivered to the transversely extending web 26 by means of the yoke member 24.

While the convolute form of casting may 35 be advantageously employed throughout the entire length thereof if desired, I preferably arrange the convolute portion adjacent the forward end only so as to not interfere with the center line of the bolster connecting rivets. I therefore provide at an intermediate point between the lugs 18 and the transverse upright web 9, a return bend 31, as clearly shown in full lines in Figure 1, whereby the side walls 2 of the casting are returned at their central portions to the 40 plane of the upper and lower portions, and in order to reinforce the convolute portions formed between the ribs 20 and 21, I provide further ribs 32 preferably in alignment with the portions 27 of the web, the ribs 45 32 extending from the web 26 to the upright web 9, as will clearly be seen from Figures 1 and 3.

The arrangement of the various walls, 50 ribs and other members of the casting, as shown on the drawings and hereinbefore described, constitutes a most effective means for receiving the variety of forces to which a combined casting is subjected.

55 All of the parts of the casting as formed, are readily accessible both for inspection and to permit the application of the casting to the car underframe, and the junctions of the various portions are arranged 60 so as to eliminate to a large extent, if not entirely, all shrinkage, cracks, checks, and

other defects incident to the manufacture of such a casting. The casting is of maximum strength for the amount of metal used and it will be seen that the casting is so devised as to distribute throughout the 70 same, all loads, strains or forces to which the various elements thereof are subjected in use.

Stop lugs are frequently subjected to column loads of a more or less eccentric nature due to the action of the draft rigging so that there is often a tendency for these lugs to bend away from the sills. That is, the lugs are often subjected to loads at an angle to their faces rather than at right 80 angles thereto, with consequent bending stress applied to the lugs and to the car sills. By forming them in the peculiar manner herein shown and described, they are adapted to resist all such actions and 85 are greatly strengthened against bending stresses so applied.

Having thus described my invention, what I claim is:

1. A body bolster center casting formed 90 with spaced vertical side walls and a floor connecting the same near their lower edges, a vertically arranged web joining the side walls over the said floor portions of the casting, the side walls being extended toward the 95 front of the casting to form continuous draft gear stops, the said extensions being of open box shape in cross section, the intermediate portions of each of said stops being connected by a longitudinally extending 100 upright flange.

2. In combination with a center sill 105 formed of a pair of spaced channel members with inturned bottom flanges, a bolster center filler having spaced side walls arranged to fit between the webs of the center sill channels, a horizontally arranged floor member connecting the said side walls near their bottom edges, the said floor member being diverted near its junction point with the side walls from its normal horizontal plane to conform to the contour of the said inturned flanges of the center sill channels, draft lugs formed at the front end of the 110 said casting, the same having horizontally arranged ribs near their lower edges, said ribs constituting extensions to the said diverted portions of the floor member.

3. In combination with a center sill 115 formed of a pair of spaced channel members with inturned bottom flanges, a bolster center filler having spaced side walls arranged to fit between the webs of the center sill channels, a horizontally arranged floor member connecting the said side walls with the bottom face thereof on line with the bottom of the center sill channels, the side walls of the castings being extended forwardly 120 to form draft gear stops, the said floor member having forward extensions above the 125 130

general plane of said floor, the same being attached to and forming stiffening ribs for the draft gear stop members.

4. A body bolster center casting formed with spaced vertical side walls and a floor connecting the same near their lower edges, a vertically arranged web joining the side walls over the said floor portions of the casting, the side walls being extended toward the front of the casting to form draft gear stops, a flange formed along the top edge of the said web, the said flange being extended forwardly along the side walls to form stiffening ribs for the draft gear stops.

5. A body bolster center casting formed with spaced vertical side walls and a floor connecting the same near their lower edges, a vertically arranged web joining the side walls over the said floor portions of the casting, the side walls being extended toward the front of the casting to form a draft gear stops, a flange formed along the top edge of the said web, the said flange being extended forwardly along the upper edge of the side walls to form stiffening ribs for the tops of the draft gear stops.

6. A body bolster center filler with forwardly extending portions spaced from each other and formed as draft lugs, the said draft lug portions having transversely arranged stop faces with a plurality of horizontally arranged ribs secured to the rear faces thereof, and vertically arranged walls connecting the edges of some of the adjacent ribs, some of the said vertical walls being disposed at the inner edges of the ribs and some at the outer edges thereof.

7. In combination with a center sill formed of a pair of spaced channel members, a bolster center filler having spaced side walls arranged to fit between the webs of the center sill channels, a horizontally arranged floor member connecting the said side walls near their bottom edges, draft lugs formed at the front ends of the said casting, the same having horizontally arranged ribs near their lower edges, said ribs constituting extensions from the said floor member.

8. A body bolster center casting having spaced parallel side walls, said side walls having at their front ends transversely arranged walls extending inwardly from the side walls toward each other and adapted to form draft gear stops adapted to present uninterrupted faces for co-action with the rear follower of the draft rigging, horizontally arranged ribs joining the rear face of each of the said stop walls with the inner face of the adjacent side wall, the side walls being omitted between some of said ribs and there being a vertical wall of metal arranged to connect these ribs at their inner edges.

9. A body bolster center casting having spaced parallel side walls, said side walls

having, at their front ends, transversely arranged walls extending inwardly from the side walls toward each other and adapted to form draft gear stops, there being an open space between the said draft gear stops suitable for the reception of the rear end of an ordinary draft gear yoke, a flanged cross member uniting the side walls, horizontally arranged ribs joining the rear faces of each of the said stop walls with the flanged cross member, the flange on said cross member being arranged in alinement with the said horizontally disposed ribs and joined to the innermost portion of the respective side walls.

10. A body bolster center filler having spaced parallel side walls, the forwardly extending portions thereon being formed as draft lugs, the transversely arranged portions of said lugs being adapted to form a follower stop, horizontally arranged ribs connected to the rear faces of said draft lugs, the said side walls being extended to form webs joining the outer edges of some of the ribs, there being vertically arranged walls joining the inner edges of other of the ribs, and a second vertically arranged wall connecting said first named vertical walls and extended across the casting at the rear of the draft lug portions to form a transverse tie therebetween.

11. A body bolster center casting formed with spaced vertical side walls and a floor connecting the same near their lower edges, a second floor connecting the said side walls at points immediately above the bottom floor member, continuous draft lugs formed on the forward end of the said casting, the same having transversely arranged stop faces with horizontally arranged ribs attached to the rear thereof, some of said ribs coinciding with and forming extensions of the said second floor member.

12. A body bolster center casting formed with spaced side walls, and a transverse connecting floor, the said casting having draft lugs at its forward end, the same being formed with transversely arranged stop faces, horizontally arranged ribs extending from the rear of the stop faces toward the rear end of the casting, the said side walls being carried forwardly to the front end of the draft lugs, and connecting the edges of the said horizontally arranged ribs, the said side walls being diverted out of their normal planes between some of the ribs, and arranged to connect said ribs at their innermost edges, the remainder of said ribs being joined by the said side walls at their outermost edges.

13. A body bolster center casting formed with draft lugs at its forward end, said draft lugs having a yoke-receiving space between their innermost faces, continuous transversely arranged walls formed on the front end of the draft lugs, and adapted to form draft gear seats, intermediate portions of said

transverse walls being extended rearwardly and around said yoke-receiving space in such manner as to tie the said lug portions together and form braces for the said stop faces thereof.

14. A body bolster center casting having spaced side walls, said side walls having at their front ends transversely arranged walls, extending inwardly toward each other and adapted to form draft gear stops, horizontally arranged ribs joining the rear face of each of the said stop walls with the inner face of the adjacent side wall, a horizontal floor member joining the said parallel walls near their bottom edge, a second horizontal floor extending between the side walls above the first mentioned floor, the plane of the said second floor coinciding with the plane of one set of the ribs, the said ribs forming extensions from the said floor, there being a vertical wall of metal joining these ribs with the next adjacent ribs, said vertical wall being extended across the casting on line with the front edge of the said second floor, and to the rear of the said draft gear stops.

15. A body bolster center casting having spaced parallel side walls, said side walls having at their front ends transversely arranged walls, extending inwardly toward each other and adapted to form draft gear stops, horizontally arranged ribs joining the rear face of each of the said stop walls with the inner face of the adjacent side wall, a horizontal floor member joining the said parallel walls near their bottom edge, a second horizontal floor extending between the side walls above the first mentioned floor, the plane of the said second floor coinciding with the plane of one set of the ribs, the said ribs forming extensions from the said floor, there being a vertical wall of metal joining these ribs with the next adjacent ribs, said vertical wall being extended across the casting on line with the front edge of the said second floor, and to the rear of the said draft gear stops, and a horizontally arranged flange at the upper extremity of the said vertical wall, the plane of the said flange coinciding with the other set of ribs, and forming a continuous horizontal bar of metal therewith.

16. A body bolster center casting having spaced parallel side walls formed with convolutions, portions of which extend inwardly toward each other and other portions of which provide draft gear stops, there being an open space between the said draft gear stops suitable for the reception of the rear end of an ordinary draft gear yoke, a transverse wall of metal connecting the said draft gear stops at the rear of the said yoke space, said wall of metal being arranged in a transverse vertical plane, there being a vertically arranged wall extending rearwardly from said transverse

wall immediately back of the yoke space, said wall being arranged in a vertically longitudinal plane.

17. A body bolster center casting having spaced parallel side walls, said side walls having at their front ends transversely arranged walls extending inwardly and toward each other and adapted to form draft gear stops, there being an open space between the said draft gear stops suitable for the reception of the rear end of an ordinary draft gear yoke, a transverse wall of metal connecting the said draft gear stops at the rear of the said yoke space, said wall of metal being arranged in a transverse vertical plane, there being a vertically arranged wall extending rearwardly from said transverse wall immediately back of the yoke space, said wall being arranged in a vertically longitudinal plane, and being extended back to the said center plate floor and arranged to form a support therefor.

18. A body bolster center casting having spaced parallel side walls, said side walls having at their front ends transversely arranged walls extending inwardly from the side walls toward each other, and adapted to form draft gear stops, a horizontally arranged reinforcing rib connecting the rear face of each of the said stop walls with the inner face of the adjacent side wall, and upright webs extending rearwardly from the adjacent faces of said stop walls for reinforcing the latter.

19. A combined back stop and tie casting involving spaced side walls, each of said side walls being provided for a portion of its length with a convoluted web, stop flanges formed on said side walls at the forward end of each convoluted web, and a cross member uniting the inwardly extending portions of the convoluted webs.

20. A combined back stop and tie casting involving spaced side walls each of which is formed with a plurality of inwardly extending longitudinally disposed flanges, vertically disposed flanges provided on said side walls and adapted to form draft gear stops, a plurality of horizontally disposed flanges united with said vertical flanges and arranged between the inwardly extending flanges of the side walls, and a cross member for connecting the said last named horizontally arranged flanges, portions of said cross member extending forwardly and forming upright flanges connecting said last named horizontally disposed flanges.

21. A combined back stop and tie casting having a plurality of spaced side walls, portions of which are formed with convolutions, stop flanges formed on said side walls adjacent one end of said convolutions, said flanges being reinforced thereby, and means including a cross member uniting the inwardly extending portions of said con-

volutions at a point in the rear of said stop flanges, said cross member being formed with a flange arranged in alinement with the inwardly extending convolutions of the side walls.

22. A combined back stop and tie casting having a plurality of spaced side walls, stop flanges formed on said side walls, means for reinforcing the said flanges, said means com-

prising a plurality of inwardly extending flanges formed on each of said side walls, and means for connecting same to said last named flanges, said means being arranged in alinement with the respective inner edges of said first named flanges.

In testimony whereof I affix my signature.

BYERS W. KADEL.
